CASE FOR A STETHOSCOPE CHEST PIECE
OR SIMILAR ARTICLE

Jacob Bodenger, 660 Meetinghouse Road,
Elkins Park, Pa.

Filed Dec. 8, 1961, Ser. No. 67,844

Term of patent 14 years

(Cl. D83—12)

FIG. 1 is a top plan view of a case for a stethoscope chest piece embodying my new design, shown in open position;

FIG. 2 is a front elevational view as shown in FIG. 1;
FIG. 3 is a rear elevational view as shown in FIG. 1;
FIG. 4 is a bottom plan view as shown in FIG. 1;
FIG. 5 is a left side elevational view as shown in

FIG. 1;
FIG. 6 is a top plan view thereof as shown in a closed position;

FIG. 7 is a front elevational view as shown in FIG. 6;
FIG. 8 is a rear elevational view as shown in FIG. 6;
FIG. 9 is a bottom plan view as shown in FIG. 6;
FIG. 10 is a left side elevational view as shown in

FIG. 6

The dominant features of my design reside in the portions shown in solid lines.

I claim:

The ornamental design for a case for a stethoscope chest piece or similar article, as shown and described.
